ABSTRACT OF THE DISCLOSURE

Disclosed is a circuit for expanding or compressing the variations of a voltage. The circuit contains two current loops. One of said loops passes a current which is created by the fluctuating voltage and therefore this current varies proportionally to said voltage. A regulated current is supplied to the second loop. The two currents are then added in a monitoring means so that the regulated current changes the variation of the fluctuating current. The percentage of variation is increased or decreased depending upon the respective polarities of the currents in the two loops.

This invention relates to a circuit for compressing or expanding the percentage of variation or tolerance of voltage between nodes of a circuit.

It is frequently desired to increase or lower the percentage of variation of the voltage of an AC or DC circuit. This may be desirable in order to permit a more accurate measurement of the voltage variation or else to enable the use of less expensive circuit components as measuring equipment. This invention accomplishes both of these advantages by adding a known regulated signal to the varying output signal to thereby lessen the effect of the variation of the monitored signal.

It is therefore an object of this invention to provide a circuit by which the tolerance of an output signal can be compressed or expanded.

It is another object of this invention to provide such a circuit in which the tolerance variation can be increased or decreased at will.

It is another object of this invention to provide such a circuit which is useful with both AC and DC circuits.

Further objects, features, and advantages of the invention will become apparent from the following description and claims when read in view of the accompanying drawings wherein like numbers indicate like parts and in which:

FIG. 1 shows a tolerance compressor circuit which is useful with DC,

FIG. 2 shows a compressor circuit which is useful with AC,

FIG. 3 shows a graph of percent of variation versus added signal in terms of the varying signal.

Referring now to the drawing, FIG. 1 shows four resistors 10, 11, 12, and 13 connected in series. Connected between the junction of resistors 10 and 11 and ground is Zener diode 15. A monitoring means 16 is connected between the junction of resistors 11 and 12 and ground, and a voltage dividing resistor 14 is connected between the junction of resistors 12 and 13 and ground. If the variation in voltage at the input V_o is desired to be compressed or expanded the variation of current I_1 must also be so compressed or expanded since by proper selection of component values the variation of I_1 can be essentially equal to the variation of V_o .

The effect of the variation of V_o , and consequently I_1 , can be changed by adding a known regulated signal I_2 to I_1 . The addition of a positive signal, with respect to I_1 ,

causes a compression of tolerance; while the addition of a negative signal increases or expands the tolerance. With Zener diode 15 poled as shown in FIG. 1 a positive current I_2 is added to I_1 ; by reversing the polarity of the Zener 15 a negative current I_2 is added to I_1 . The effect of the addition of a regulated current I_2 on the variation of current I_1 can be demonstrated by considering the current I_m passing through monitor 16. For example, in FIG. 1 the current passing through monitor 16 is

$$I_m = I_1 + I_2 \pm 0.25 I_1 \quad (1)$$

Equation 1 shows an assumed 25% variation of I_1 for purposes of illustration; however, any percentage of variation can be compressed or expanded. The 25% variation is decreased by substituting for current I_2 a multiple (A) of current I_1 .

Equation 1 then becomes

$$I_m = I_1 + A I_1 \pm 0.25 I_1 \quad (2)$$

In this manner the variation seen by monitor 16 becomes a $\pm 0.25 I_1$ variation over a nominal current of $I_1 + A I_1$ which gives a variation of

$$\pm \left[\frac{0.25 \times 100}{1+A} \right] \% \quad (3)$$

Assuming that it is desired to compress the 25% variation to a 12.5% variation this can be done by regulating current I_2 such that $I_2 = I_1$ (i.e. $A = 1$). Substituting this value into Equation 1, the equation then becomes

$$I_m = 2I_1 \pm 0.25 I_1$$

which in accordance with Equation 3 becomes

$$\pm \left[\frac{0.25 \times 100}{1+1} \right] \%$$

This is a current variation of ± 0.25 on a nominal current of two which gives a current variation of 12.5% as desired. By changing the relationship of I_1 and I_2 any percentage of variation can be obtained. This is shown in Table 1 where A represents the ratio of I_1 to I_2 .

Table I.— I_2 positive

A:	$\pm$ percent variation seen by monitor 16
0	25.0
.25	20.0
.5	16.6
1	12.5
1.5	10.0
2	8.3
3	6.25
4	5.0
5	4.16
6	3.57
7	3.13

As shown in the table, by allowing the coefficient A to vary from 0.25, which gives a percent variation of $\pm 20\%$, to a value of 7, the percent variation can be decreased to $\pm 3.13\%$. It is obvious that the percent variation can be decreased further simply by increasing the relationship of I_1 to I_2 .

In order to expand the tolerance it is necessary to reverse the polarity of Zener diode 15 and reference voltage VDC as shown in FIG. 1. By doing this the current I_2 is negative with respect to the current I_1 . The effect of this is to decrease the value of current as shown in Equation 1. For this reason when the ratio to I_2 of I_1 is between zero and one ($0 < A < 1$) the percent of variation changes from a theoretical infinite at the value of $A = 1$ to $\pm 25\%$ at the value of $A = 0$. For values of $1 < A < 2$ tolerance expansion is also accomplished but a reversal of monitor 16 polarity is required. For $A > 2$ tolerance compression

with monitor 16 polarity reversal occurs. This is shown in Table 2.

Table II.— I_2 negative

A: $\pm\%$ variation seen by monitor 16

0	25
.25	33.3
.5	50
1	00
1.25	100
1.5	50.0
2	25.0
3	12.5
4	8.3
5	6.25
6	5.0
7	4.16

Referring now to FIG. 3, the solid curve 22 shows the percent variation versus the AI_1 current relationship for positive values of I_2 and broken curve 23 is a similar curve for values when I_2 is negative with respect to I_1 .

FIG. 2 shows the circuit of FIG. 1 wherein the circuit is adapted for use with AC inputs. In order to accomplish this, diode 20, resistor 17 and capacitor 18 are added to the regulated end of the circuit and diode 21 and capacitor 19 are added to the monitor end of the circuit. Diode 20 is added to rectify the AC signal assuring that only positive values of current are presented to resistor 17 and capacitor 18 which smooths the input current. Diode 21 and capacitor 19 perform a similar function on the monitor end. The operation of the circuit is now the same as that of the FIG. 1 circuit. The circuit as shown in FIG. 2 is useful in compressing the variation of voltage V_o . In order to adapt the circuit for expanding the V_o tolerance it is necessary to reverse the polarity of Zener diode 15 and diode 20.

In the above description both the input current I_2 and current to be monitored I_1 have been either AC or DC. For example, in FIG. 1 both currents are DC while in FIG. 2 both are AC. The similarity of current forms is not essential to the operation of the invention. FIG. 1 can be modified to add an AC input current I_2 to a DC monitored current I_1 by adding diode 20, capacitor 17 and resistor 18 to the input end of the circuit in the same manner as shown in FIG. 2. Alternatively, FIG. 1 can be modified to add a DC input current I_2 to an AC monitored current I_1 by adding capacitor 19 and diode 21 to the monitored end of the circuit in the same manner as shown in FIG. 2. It is now evident that four combinations are possible.

- (1) DC input with DC monitored
- (2) AC input with AC monitored
- (3) DC input with AC monitored
- (4) AC input with DC monitored

Although this invention has been described with respect to particular embodiments thereof, it is not to be so limited, as changes and modifications may be made therein which are within the spirit and scope of the invention as defined by the appended claims.

I claim:

1. A monitoring circuit capable of compressing or expanding variations in a monitored signal comprising moni-

toring means having first and second terminals, first conductive means connected to said first and second terminals for receiving an input signal and supplying a first current to said monitoring means, second conductive means connected to said first and second terminals for receiving a reference voltage and supplying a regulated second current to said monitoring means, said first conductive means comprising a voltage divider means, and said second conductive means comprising a T configuration voltage divider means including a shunt connected Zener diode for regulating the second current through said monitoring means.

2. A monitoring circuit as defined by claim 1 wherein said reference voltage is a DC voltage, and the polarities of said DC voltage and said Zener diode are arranged so that said first and second currents are cumulative in said monitoring means thereby compressing variations in said monitored signal.

3. A monitoring circuit as defined by claim 1 wherein said reference voltage is a DC voltage, and the polarities of said DC voltage and said Zener diode are arranged so that said first and second currents are opposing in said monitoring means thereby expanding variations in said monitored signal.

4. A monitoring circuit as defined by claim 1 wherein said second conductive means further includes a series connected diode and a shunt connected resistor-capacitor parallel combination for receiving said reference voltage, said reference voltage being AC.

5. A monitoring circuit as defined by claim 4 wherein the polarities of said shunt diode and said series diode are arranged so that said first and second currents are cumulative in said monitoring means thereby compressing variations in said monitored circuit.

6. A monitoring circuit as defined by claim 4 wherein the polarities of said shunt diode and said series diode are arranged so that said first and second currents are opposing in said monitoring means thereby expanding variations in said monitored circuit.

7. A monitoring circuit as defined by claim 1 wherein said first conductive means includes a series connected diode and a shunt capacitor for receiving said input signal, said input signal being AC.

8. A monitoring circuit as defined by claim 4 wherein said first conductive means includes a series connected diode and a shunt capacitor for receiving said input signal, said input signal being AC.
